Specification for Design.

Patented June 20, 1916.

Application filed April 10, 1916. Serial No. 90,257. Term of patent 7 years.

To all whom it may concern:

Be it known that I, SAMUEL N. GOODMAN, a citizen of the United States, residing in Philadelphia, county of Philadelphia, and State of Pennsylvania, have invented a new, original, and ornamental Design for Lace Edging, of which the following is a specification, reference being had to the accompanying drawings, which form a part thereof.

The drawing is a plan view of a portion of lace edging showing my design.

The same comprises a heading or sewing-on edge *a*, a relatively open space bounded by longitudinally extending chain threads and spanned by sections of a relatively

coarse cross thread, *b*, a body *c* composed of a number of longitudinally extending chain threads united by relatively fine cross threads, a part *d* similar to *b*, and an ornamental scallop forming a border or tip *e*.

I claim—

The ornamental design for a lace edging, as shown and described.

In testimony of which invention, I have hereunto set my hand, at Philadelphia, on this 3rd day of April, A. D. 1916.

SAMUEL N. GOODMAN.
